(57) **CLAIM**

The ornamental design for a living body information sensor, as shown.

DESCRIPTION

FIG. 1 is a front view of a living body information sensor of a first embodiment showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is an enlarged front view taken along line 7-7 of FIG. 1 thereof;

FIG. 8 is an enlarged front view taken along line 8-8 of FIG. 1 thereof;

FIG. 9 is an enlarged front view taken along line 9-9 of FIG. 1 thereof;

FIG. 10 is an enlarged rear view taken along line 10-10 of FIG. 2 thereof;

FIG. 11 is an enlarged bottom plan view taken along line 11-11 of FIG. 4 thereof;

FIG. 12 is an enlarged rear view taken along line 12-12 of FIG. 2 thereof;

FIG. 13 is an enlarged top plan view taken along line 13-13 of FIG. 3 thereof;

FIG. 14 is a referential front view showing a transparent portion, which is indicated with oblique lines thereof;

FIG. 15 is a referential rear view showing a transparent portion, which is indicated with oblique lines thereof;

FIG. 16 is a referential front view showing a translucent portion, which is indicated with oblique lines thereof;

FIG. 17 is a referential bottom plan view showing a translucent portion, which is indicated with oblique lines thereof;

FIG. 18 is a referential cross-sectional view taken along line 18-18 of FIG. 16 thereof;

FIG. 19 is a perspective view thereof;

FIG. 20 is a front view of a living body information sensor of a second embodiment showing our new design;
FIG. 21 is a rear view thereof;
FIG. 22 is a top plan view thereof;
FIG. 23 is a bottom plan view thereof;
FIG. 24 is a right side view thereof;
FIG. 25 is a left side view thereof;
FIG. 26 is an enlarged front view taken along line 26-26 of FIG. 20 thereof;
FIG. 27 is an enlarged front view taken along line 27-27 of FIG. 20 thereof;
FIG. 28 is an enlarged front view taken along line 28-28 of FIG. 20 thereof;
FIG. 29 is an enlarged rear view taken along line 29-29 of FIG. 21 thereof;
FIG. 30 is an enlarged bottom plan view taken along line 30-30 of FIG. 23 thereof;

FIG. 31 is an enlarged rear view taken along line 31-31 of FIG. 21 thereof;
FIG. 32 is an enlarged top plan view taken along line 32-32 of FIG. 22 thereof;
FIG. 33 is a referential front view showing a transparent portion, which is indicated with oblique lines thereof;
FIG. 34 is a referential rear view showing a transparent portion, which is indicated with oblique lines thereof;
FIG. 35 is a referential front view showing a translucent portion, which is indicated with oblique lines thereof;
FIG. 36 is a referential cross-sectional view taken along line 36-36 of FIG. 35 thereof; and,
FIG. 37 is a perspective view thereof.
The broken line showing of structural features are included for the purpose of illustrating non-claimed subject matter and forms no part of the claimed design.
